Attorney.

UNITED STATES PATENT OFFICE.

JAMES W. VAN METER, OF SAN FRANCISCO, CALIFORNIA.

CHLORINATION APPARATUS.

1,400,107.

Specification of Letters Patent. Patented Dec. 18, 1921.

Application filed February 23, 1921. Serial No. 447,107.

To all whom it may concern:

Be it known that I, JAMES W. VAN METER, a citizen of the United States of America, residing at No. 2977 Clay street, city of San Francisco, in the county of San Francisco and State of California, have invented certain new and useful improvements in Chlorination Apparatus, of which the following is a specification.

The present invention is an improved chlorination apparatus.

The primary object of the invention is to provide a safe, efficient and inexpensive apparatus with which liquid chlorin may be used in the preparation of different chemicals of fluids for producing various bleaching, disinfecting and oxidizing agents.

Liquid chlorin when liberated forms a deadly gas and the greatest care is necessary in handling it to safe guard human life. In devices of this character it has been customary to provide intricate valves and mechanisms which require silver plating or other costly materials as protection against the corrosive action of the chlorin.

These factors render the apparatus very expensive and require expert manipulation and care in upkeep.

The present invention contemplates a relatively simple apparatus in which liquid chlorin may be used at low pressure and with which a layman or attendant unfamiliar with chemistry may prepare any given mixture or formula repeatedly without danger.

In the preparation of various bleaches and disinfectants, in which chlorin is employed as an active agent, the exclusion of direct light is an advantage. I have therefore provided an apparatus with certain sight feed installations by means of which an attendant may be sure that chlorination is being effected and by which the exact proportions of the ingredients may be regulated.

My apparatus may be used with safety in a closed room and the chlorinated products, being at all times under pressure, can be withdrawn while chlorination is going on within.

This fact makes my device especially useful in hospitals, water purification plants, laundries, bleach and dyeing establishments.

In this specification and the annexed drawings, the invention is illustrated in the

form considered to be the best, but it is to be understood that the invention is not limited to such form, because it may be embodied in other forms and it is also to be understood that in and by claims following the description it is desired to cover the invention in whatever form it may be embodied.

In the accompanying 3 sheets of drawings;

Fig. 1 is a perspective view of my chlorination apparatus of one cell capacity.

Fig. 2 is a similar view showing a three cell installation served by the same pump and chlorin container.

Fig. 3 is an enlarged vertical cross section of my apparatus showing the conduits and valves arrangement.

Fig. 4 is a fragmentary section of Fig. 3 taken on a vertical plane perpendicular to that on which Fig. 3 is taken.

Referring to the drawings the numeral 1 indicates the rear wall of a cabinet designed to be secured to a wall of a room.

Side walls 2 and 3 are mortised as shown at 4 and 6 to receive top and bottom walls 7 and 8 respectively.

A front wall 9 incloses the cabinet to make it light proof and this wall is inset as shown at 11 to form a projecting ledge 35 on the bottom or floor piece 8 to support a sight feed glass 12 which is protected against displacement at the top and bottom by cleats 13 and 14 respectively.

An inverted bottle or container 16, open only at the bottom, rests on the floor 8 and the neck 17 projects through an aperture 18 in the floor.

The neck 17 of the bottle has a flange 19 for engagement by a plastic material 21 which secures to the bottle a porcelain casting 22. This casting has an annular depending flange 23. A layer 24 of wax or plastic material separates this flange from a metallic threaded ring 26 adapted to engage threads on glass bulb 27. The casting 22 is provided with bosses for pipe connection with pipes to be later described. These bosses are circumferentially distributed on the casting end and are indicated at 28, 29, 31 and 32. Another similar boss 33 is provided for engaging a by-pass pipe 34 communicating with the sight feed pipe 12. By this arrangement fluid in the bottle 16 seeks its level in the sight feed tube 12.

When the bulb 27 is threaded into the casting flange 23 and against a rubber gasket 36 the bottle 16 is entirely closed but for the bosses before mentioned.

5 Fluid to be chlorinated in the bottle 16 is introduced through boss 29, through a pipe 37 provided with a check valve 38.

In order that storage receptacles such as A, B and C containing respectively water, 10 soda, and caustic may be remote from the machine as, for instance, in a basement I prefer to use a pipe line from the receptacle to the bottle 16 and to force the fluid from the receptacles A, B, and C to the bottle 16 15 by the use of a compressed air pipe line 39 supplied by a pump 41.

The air line pipe 39, Fig. 1, is provided with a T 42 and valves 43 and 44 are provided to divert the compressed air both 20 ways on said line, one way for filling the bottle 16 as just described and another way for agitation means to be later described.

As fluid is thus forced by compressed air coming through pipe 39 and displacing said 25 fluid in the containers and driving the fluid through pipe 37 it enters the casting 22 filling the bottle 16 to a desired level indicated on the sight tube 12 which is fed by by-pass 34. The fluid also fills the bulb 27 through 30 ports 46 and 47 in the casting 22.

As the fluid rises within the bottle 16 the air in said bottle is displaced through a tube 48 leading to casting 22 and out at boss 32 and through a pipe 49 to an exhaust pipe 51 35 from which a pipe 52 leads downwardly to a point beneath the surface of a fluid 53 in a container 54.

This fluid may be any suitable chlorin absorbent adapted to arrest escape of excess 40 chlorin due to overcharging and thereby prevent danger and obnoxious fumes.

The pipe 52 is provided with a bulb 56 for detecting chlorin as will be later described.

Assuming that the bottle 16 has been 45 filled to the desired level and it is to be chlorinated, liquid chlorin from a container 57 is admitted through valves 58 and 59 to a pipe 61 connected by a pipe coupling to a pipe 62 leading to a goose neck pipe 63 extending 50 through the top 4 of the cabinet and terminating in the boss 31, Fig. 4. A passage 64 connects the pipe 63 with a pipe 66 depending from casting 22 within the bulb 27 to a point beneath the surface of a body of 55 corundum particles 67.

The function of the corundum particles is to serve as a diffuser for breaking up the chlorin into small particles for more ready absorption.

60 When the fluid to be chlorinated has reached its limit of absorption the excess chlorin will pass off through air discharge pipes 48 and 51 to the absorption vessel 54.

The presence of chlorin in excess will be 65 shown in bulb 56 which is transparent glass

and readily indicates the green color of chlorin.

In order to withdraw chlorinated fluid from the interior of bottle 16, I provide a pipe 68, Fig. 3, which connects to boss 28 70 and to T shaped valve 69 the vertical passage of which is provided with a rubber bushing 71 in which rotates a glass tube 72.

This tube is provided with a rubber grip 73 to facilitate the rotation of the tube 72 75 to register a port 74 with the pipe 68 for withdrawing fluid.

The valve is closed by rotating the pipe 72.

As fluid is withdrawn by this means from bottle 16, air to take its place is admitted 80 through a pipe 76 leading into a water seal or container 77 and extending downwardly therein to a point below the surface of water 78.

This container has three apertures on the 85 top, one for the pipe 76, one for filling with water 78, and one for a return bend pipe 79 which connects through a T 81 with sight feed glass 12 and through an elbow 82 and down pipe 83 with exhaust pipe 51. 90

The water seal thus described operates to admit air to bottle 16 as fluid is withdrawn therefrom through pipe 72, the air entering by way of pipes 76 and 79.

It also operates as a safety valve in case 95 the pipe leading to absorption tank 54 becomes choked or undue pressure is generated in the bottle 16 due to heat or other chemical action.

An important feature of my invention 100 lies in the arrangement I provide for agitating and aerating and mixing the contents of the bottle 16.

That portion of the pipe 39, Fig. 1, above the T 42 is provided with a flexible conduit 105 84 which extends outwardly from the side wall 2 of the cabinet and terminates in a pipe coupling 86. Now, if pipe 61 be disconnected from pipe 62 and pipe 62 be connected to conduit 84, it will be seen that compressed air will enter the bulb 27 through the chlorin 110 passage 63. If the pump 41 now be operated the air will be diffused by the corundum particles and agitate and aerate the contents of bottle 16. 115

It will be seen that I have provided an inverted container the major portion of which is contained in a light proof cabinet and have also provided a sight feed whereby the introduction of chlorin or air is visible at all times and which is at the same time readily removable for cleansing or replenishment.

It will be seen that no escape of chlorin is possible from my apparatus other than 125 through a body of liquid.

The glass tube 12 is suitably graduated to indicate the amount withdrawn from the bottle 16, as shown at 88. This dispenses with graduates or measuring devices in mix- 130

ing ingredients of dyes or bleaches when the device is used in multiple as shown in Fig. 2.

It is obvious that the bottle 16 might be 5 made of clay, porcelain or other suitable opaque material if desired to obviate the necessity of the cabinet and I wish to cover in the appending claims either form of structure.

10 I claim:

1. A chlorin apparatus comprising a light proof cabinet, an inverted bottle in said cabinet, a relatively small bulb of transparent material secured to the open end of said bottle and extending out of said cabinet, means for introducing fluid to be chlorinated to said bottle and bulb, and means for introducing chlorin gas under pressure to chlorinate said fluid.

20. 2. A chlorin apparatus comprising a light proof cabinet, an inverted bottle in said cabinet, a relatively small bulb of transparent material secured to the open end of said bottle and extending out of said cabinet, means 25 for introducing fluid to be chlorinated to said bottle and bulb, means for introducing chlorin gas under pressure to chlorinate said fluid, and means for conducting escaping air from said bottle as fluid is introduced.

30. 3. A chlorin apparatus comprising a light proof cabinet, an inverted bottle in said cabinet, a relatively small bulb of transparent material secured to the open end of said bottle and extending out of said cabinet, means for introducing fluid to be chlorinated to said bottle and bulb, means for introducing chlorin gas under pressure to chlorinate said fluid, and means for conducting escaping 35 air through a fluid trap before discharging to the atmosphere.

40. 4. A chlorin apparatus comprising a light proof cabinet, an inverted bottle in said cabinet, a relatively small bulb of transparent material secured to the open end of said bottle and extending out of said cabinet, means for introducing fluid to be chlorinated to said bottle and bulb, means for introducing chlorin gas under pressure to chlorinate 45 said fluid, and means for discharging from said bottle excess chlorin through a liquid absorbent.

50. 5. A chlorin apparatus comprising an inverted container of opaque material, a relatively small bulb of transparent material attached to the bottom of said container, a pipe line connected with said bulb and adapted to 55 fill said bulb and said container with fluid to

be chlorinated, a second pipe line adapted to conduct chlorin gas into said bulb and said container and terminating within said bulb to form a visible chlorin feed, and a conduit adapted to permit escape of air from said container as it is displaced by liquid or gas.

6. A chlorin apparatus comprising an inverted container of opaque material, a relatively small bulb of transparent material attached to the bottom of said container, a pipe line connected with said bulb and adapted to fill said bulb and said container with fluid to 60 be chlorinated, a second pipe line adapted to conduct chlorin gas into said bulb and said container and terminating within said bulb to form a visible chlorin feed and a conduit adapted to permit escape of air from said container as it is displaced by liquid or gas, 65 and a transparent tube communicating with said container near the base thereof.

7. A chlorin apparatus comprising an inverted container of opaque material, a relatively small bulb of transparent material attached to the bottom of said container, a pipe line connected with said bulb and adapted to fill said bulb and said container with fluid to 70 be chlorinated, a second pipe line adapted to conduct chlorin gas into said bulb and said container and terminating within said bulb to form a visible chlorin feed, a conduit adapted to permit escape of air from said container as it is displaced by liquid or gas, 75 and a transparent tube communicating with said container near the base thereof.

8. A chlorin apparatus comprising an inverted container of opaque material, a relatively small bulb of transparent material 80 attached to the bottom of said container, a pipe line connected with said bulb and adapted to fill said bulb and said container with fluid to be chlorinated, a second pipe line adapted to 85 conduct chlorin gas into said bulb and said container and terminating within said bulb to form a visible chlorin feed, a conduit adapted to permit escape of air from said container as it is displaced by liquid or gas, 90 and a transparent tube communicating with said container near the base thereof.

9. A chlorin apparatus comprising an inverted container of opaque material, a relatively small bulb of transparent material 95 attached to the bottom of said container, a pipe line connected with said bulb and adapted to fill said bulb and said container with fluid to be chlorinated, a second pipe line adapted to 100 conduct chlorin gas into said bulb and said container and terminating within said bulb to form a visible chlorin feed and a conduit adapted to permit escape of air from said container as it is displaced by liquid or gas, 105 and a suitable diffusing material in said bulb for the purpose of breaking chlorin into small particles as it enters for more rapid absorption.

9. In a chlorination apparatus a bottle of opaque material, and a relatively small bulb 110 of transparent material removably attached to said bottle to form a visible means for viewing the chlorination process and detecting impurities in the fluid.

In testimony whereof I affix my signature. 115
JAMES W. VAN METER.
